BLAST RESISTANT BUILDING

Phillip Graham, Pittsburgh, Pa.

Application December 16, 1953, Serial No. 28,105

Term of patent 14 years

(Cl. D13—1)

To all whom it may concern:

Be it known, that I, Phillip Graham, a citizen of the United States of America, residing at Pittsburgh, county of Allegheny and Commonwealth of Pennsylvania, have invented a new, original, and ornamental Design for a Blast Resistant Building, of which the following is a specification, reference being had to the accompanying drawing, forming part thereof, wherein:

Figure 1 is a plan view of a blast resistant building showing my new design;

Figure 2 is a perspective view taken along line 1—1 of Figure 1;

Figure 3 is a perspective view taken along line 2—2 of Figure 1; and

Figure 4 is a fragmentary view showing the retractable

door-canopy in a closed position taken on the line 4—4 of Figure 1.

I claim:

The ornamental design for a blast resistant building, substantially as shown.
